UNITED STATES PATENT OFFICE.

II. CLAY BASCOM, OF TROY, AND TOBIAS S. HEISTER, OF LANSINGBURG,
NEW YORK, ASSIGNORS TO SAID BASCOM.

DESIGN FOR A PARLOR-STOVE.

SPECIFICATION forming part of Design No. 15,396, dated September 16, 1884.

Application filed June 17, 1884. Term of patent 7 years.

To all whom it may concern:

Be it known that we, II. CLAY BASCOM, a citizen of the United States, residing in the city of Troy, in the county of Rensselaer and State of New York, and TOBIAS S. HEISTER, a citizen of the United States, residing in the village of Lansingburg, in said county and State, have jointly invented and produced a new and original Design for Parlor-Stoves, of which the following is a specification, reference being had to the accompanying cut, print, or engraving of a stove having said design.

This design relates to the shape of the stove and to the ornamentation of its parts, as hereinafter described, and shown in the accompanying illustration.

One distinguishing feature of this design is the configuration and ornamentation of the main portion of the stove, consisting of the rectangular projecting top plate, A, having the outer border, e, and inclined surface e'; the end B and front C of the upper section, each of a general rectangular form, and curved concavely outward at the upper parts, as shown at a a, and the part C being narrower at its middle than at its ends, and curved concavely along its lower edge; the projecting plate D, of a general rectangular shape horizontally, inclined on top and arched in front; the front E and end F of the middle section, each of a general rectangular form, and curved concavely outward at the upper parts, as shown at b b', and extended upward under and to the plate D; the flat rectangular projecting top plate, G, of the base section; the rectangular front H and end plate, I, of the base section, and the flat rectangular hearth-plate J.

The configuration and ornamentation of the cover K consists of its rectangular outline, flat top e, lower inclined border, e', intermediate inclined part, e'', and the front ornament, d.

The design for the top A consists of its rectangular form, plane outer border, e, inclined molded surface e', end ornaments, f, and ornamented name part g.

The design for the end B of the upper section is distinguished by its concavely-curved upper part, and the rectangular panel having therein the central rosette and quadrilateral

ornaments h, the upper vine and leaf ornaments, i, and the lower corner flaring ornaments, i'.

The design for the front C of the upper section is distinguished by its concavely-curved upper portion at a, its contracted middle part, 55 the central ornaments, k, angular end ornaments, k', and the intermediate vine-form ornaments, j.

The design for the plate D is distinguished by its arched front portion, l, and straight angular end parts, l', the central semi-rosette ornaments, m m', and the lateral rows of flaring ornaments n n'.

The design for the ornamental plate L on the upper part of the front of the middle section is distinguished by having its outline in the general form of a segment of a circle, and having the lower laterally-flaring ornaments, o, the flaring top ornament, o', the central quadrilateral ornamental part, p, and the vine-form ornaments p'.

The design for the front E of the middle section consists of the two rectangular upper doors, M, each having four rectangular panes, q, and curved reversely in the horizontal direction, the oblong rectangular lower doors, N, each having the two rectangular panes q', and curved reversely in the horizontal direction, and the main plate O, likewise curved reversely in the horizontal direction, and having the band r between said upper and lower doors, the concavely-curved upper corner parts, b, and the sub-circular top extension, r'.

The design for the end F of the middle section consists of the upper flat rectangular door, 85 P, having the four rectangular panes s, the lower flat rectangular door, Q, having two rectangular panes, s', and the generally flat and rectangular main plate R, having the horizontal band t between the doors and the concavely-curved upper part, b'.

The design for the foot-rest S consists of the two reversely-curved ornamented brackets u, the intermediate rail, u', and the pointed extensions u'.

The design for the front H of the lower section is distinguished by the oblong rectangular doors T, having the compound border-

(over)

molding v , the series of vertically-oblong rectangular apertures v' , and the intermediate rosette and scale-form ornaments, v'' .

The design for the end plate, I, of the lower section consists of the outer rectangular flat portion, w , the raised panel-border w' , and the compound panel ornament w'' .

The design for the legs U consists of the upper flat parts, x , meeting at a right angle, and having the leaf ornaments x' , and the convexly and concavely curved portion y , having the ornament y' .

The design for the separable skirting-plates V, between the legs, consists of the central downwardly-projecting quadrilateral ornaments z , the lateral vine-form ornaments z' , and the intermediate ornaments, z'' .

The whole design embraces the shape and ornamentation of the legs U, skirting V, base-plate J, front H, and end I of the base-section, plate G, foot-rest S, front E, and end F of the middle section, separable ornamental plate L, division-plate D, end B, and front C of the upper section, top A, and the movable cover K.

25 We claim as new—

1. In a design for a stove, the configuration and ornamentation of the main portion, consisting of the top plate, A, end B, and front C of the upper section, plate D, front E, and end F of the middle section, plate G, front H, and end plate, I, of the base-section, and the hearth-plate J, as shown and described.

2. In a design for a stove, the shape and ornamentation of the cover K, embracing the parts e , e' , e'' , and d , as shown and described.

3. In a design for a stove, the shape and ornamentation of the top plate, A, consisting of the parts e , e' , f , and g , as shown and described.

4. In a design for a stove, the configuration and ornamentation of the end B of the upper section, embracing its concavely-curved upper part, and the rectangular panel having the ornaments h i i' , as shown and described.

5. In a design for a stove, the shape and ornamentation of the front C of the upper section, embracing the parts k k' j , as shown and described.

6. In a design for a stove, the shape and ornamentation of the plate D, consisting of the

parts l l' , and the ornaments u u' and u u'' , as shown and described.

7. In a design for a stove, the configuration and ornamentation of the front plate, L, having the ornaments a a' p p' , as shown and described.

8. In a design for a stove, the configuration and ornamentation of the front E of the middle section, consisting of the doors M, having the panes q , doors N, having the panes q' , and the main plate O, having the band r , and the top extension, r' , all shaped as shown and described.

9. In a design for a stove, the configuration and ornamentation of the end F of the middle section, consisting of the door P, having the panes s , the door Q, having the panes s' , and the main plate R, having the band t and curve u' , all shaped as shown and described.

10. In a design for a stove, the configuration and ornamentation of the foot-rest S, consisting of the parts u u' u'' , as shown and described.

11. In a design for a stove, the configuration and ornamentation of the front H of the base-section, embracing the doors T, having the ornamental parts v v' v'' , all shaped as shown and described.

12. In a design for a stove, the shape and ornamentation of the end plate, I, of the base-section, consisting of the parts w , w' , and w'' , as shown and described.

13. In a design for a stove, the shape and ornamentation of the legs U, embracing the parts x x' y y' , as shown and described.

14. In a design for a stove, the configuration and ornamentation of the skirting-plates V, consisting of the parts z z' z'' , as shown and described.

15. A design for a stove, consisting of the parts U, V, J, H, I, G, S, E, F, L, D, B, C, A, and K, shaped and ornamented as set forth.

In testimony whereof we hereunto set our hands, in the presence of two subscribing witnesses, this 14th day of June, 1884.

H. CLAY BASCOM.
TOBIAS S. HEISTER.
